FIG. 2 shows a top view of the first embodiment.

FIG. 3 shows a front view of the first embodiment.

FIG. 4 shows a right-side view of the first embodiment. A left-side view of this embodiment is a mirror image of this figure.

FIG. 5 shows a back view of the first embodiment.

FIG. 6 shows a bottom view of the first embodiment.

FIG. 7 shows a perspective view of a second embodiment of a design for an integrated tabbed note and clip kit.

FIG. 8 shows a top view of the second embodiment.

FIG. 9 shows a front view of the second embodiment.

FIG. 10 shows a right-side view of the second embodiment. A left-side view of this embodiment is a mirror image of this figure.

FIG. 11 shows a back view of the second embodiment.

FIG. 12 shows a bottom view of the second embodiment.

FIG. 13 shows a perspective view of a third embodiment of a design for an integrated tabbed note and clip kit.

FIG. 14 shows a top view of the third embodiment.

FIG. 15 shows a front view of the third embodiment.

FIG. 16 shows a right-side view of the third embodiment. A left-side view of this embodiment is a mirror image of this figure.

FIG. 17 shows a back view of the third embodiment.

FIG. 18 shows a bottom view of the third embodiment.

FIG. 19 shows a perspective view of a fourth embodiment of a design for an integrated tabbed note and clip kit.

FIG. 20 shows a top view of the fourth embodiment.

FIG. 21 shows a front view of the fourth embodiment.

FIG. 22 shows a right-side view of the fourth embodiment. A left-side view of this embodiment is a mirror image of this figure.

FIG. 23 shows a back view of the fourth embodiment.

FIG. 24 shows a bottom view of the fourth embodiment.

FIG. 25 shows a perspective view of a fifth embodiment of a design for an integrated tabbed note and clip kit.

FIG. 26 shows a top view of the fifth embodiment.

FIG. 27 shows a front view of the fifth embodiment.

FIG. 28 shows a right-side view of the fifth embodiment. A left-side view of this embodiment is a mirror image of this figure.

FIG. 29 shows a back view of the fifth embodiment.

FIG. 30 shows a bottom view of the fifth embodiment.

FIG. 31 shows a perspective view of a sixth embodiment of a design for an integrated tabbed note and clip kit.

FIG. 32 shows a top view of the sixth embodiment.

FIG. 33 shows a front view of the sixth embodiment.

FIG. 34 shows a right-side view of the sixth embodiment. A left-side view of this embodiment is a mirror image of this figure.

FIG. 35 shows a back view of the sixth embodiment.

FIG. 36 shows a bottom view of the sixth embodiment.

FIG. 37 shows a perspective view of a seventh embodiment of a design for an integrated tabbed note and clip kit.

FIG. 38 shows a top view of the seventh embodiment.

FIG. 39 shows a front view of the seventh embodiment.

FIG. 40 shows a right-side view of the seventh embodiment. A left-side view of this embodiment is a mirror image of this figure.
